UNITED STATES PATENT OFFICE.

JOHN C. CUMMINGS, OF CLEVELAND, OHIO, ASSIGNOR TO THE CLEVELAND
MACHINERY SCREW COMPANY, OF SAME PLACE.

DESIGN FOR A DUST-CAP FOR BALL-BEARINGS.

SPECIFICATION forming part of Design No. 29,522, dated October 18, 1898.

Application filed September 12, 1898. Serial No. 690,801. Term of patent 14 years.

To all whom it may concern:

Be it known that I, JOHN C. CUMMINGS, a citizen of the United States, residing in Cleveland, in the county of Cuyahoga and State of Ohio, have invented and produced a new and original Design for Dust-Caps for Ball-Bearings, of which the following is a specification, reference being had to the accompanying drawings, forming a part thereof.

10 Figure 1 is a perspective view of a dust-cap showing my new design. Fig. 2 is a central sectional view through one side of the same.

A dust-cap is usually made of a single piece of metal and comprises a short cylindrical body and an inwardly-turned annular flange at one end of said body.

15 My design relates to the body part of such a dust-cap. The leading or material features of my design consist of an internal spiral

thread on said cylindrical body, an external 20 complementary spiral groove on said body, and a knurled external surface on said body.

In the drawings, A represents the body; a, the internal spiral thread; a', the external complementary spiral groove, and a² the 25 knurled external surface of said body.

Having described my invention, what I claim as new, and desire to secure by Letters Patent, is—

The design for a dust-cap for ball-bearings 30 as herein shown and described.

In testimony whereof I hereunto affix my signature in the presence of two witnesses.

JNO. C. CUMMINGS.
